US00D865521S

(12) **United States Design Patent** (10) Patent No.: **US D865,521 S**
(45) Date of Patent: **** Nov. 5, 2019**

(54) **PACKAGING CONTAINER**

- (71) Applicant: **SEIKO EPSON CORPORATION**,
Tokyo (JP)
- (72) Inventors: **Taku Ishizawa**, Matsumoto (JP);
Noriyuki Fukasawa, Shiojiri (JP);
Manabu Akahane, Nagano (JP); **Izumi**
Washizawa, Shiojiri (JP); **Yasuhiko**
Fuchigami, Shiojiri (JP)
- (73) Assignee: **SEIKO EPSON CORPORATION**,
Tokyo (JP)
- (**) Term: **15 Years**
- (21) Appl. No.: **29/685,149**
- (22) Filed: **Mar. 26, 2019**

Primary Examiner — Michael A. Pratt
Assistant Examiner — Wendy Arminio

(57) **CLAIM**

The ornamental design for a packaging container, as shown
and described.

DESCRIPTION

FIG. 1 is a front, top and right side perspective view of a
packaging container showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines illustrate portions of the packaging con-
tainer that form no part of the claimed design.

1 Claim, 7 Drawing Sheets
